ELECTRIC CONNECTOR

Milton M. Kauffman, Los Angeles, Calif.

Original application March 31, 1936, Serial No. 71,841. Divided and this application April 3, 1937, Serial No. 134,746

8 Claims. (Cl. 173—328)

My invention relates in general to means for insulating electric devices from their supports and for connecting such electric devices to an electric circuit, and relates in particular to electric insulating and connecting means having especial utility with glow tubes of the general character employed in electric signs. The subject matter of the following specification and claims is a division of my pending application, Serial No. 71,841, "Electric connector and insulator attachment", filed March 31, 1936.

The invention has utility in the insulation and connection of various types of electric devices, but in view of the fact that its greatest use will probably be in conjunction with electric display devices, such as neon signs, the following disclosure of the invention will be, for the purpose of simplicity, limited to the use of the invention as a means for insulating electric members of the general character of gas-filled glow tubes and connecting electric feed conductors or wires to the terminals of the tubes. In illuminated display members of this general character, a supporting structure is generally employed having a front wall which may be sheet metal and adjacent to which the gas filled glow tubes are secured. The tubes are supported in spaced relation to the front face of the wall by suitable brackets or posts.

It is an object of the invention to provide means enabling the connection of electric conductors to the end of the tubes in such a manner that such connection will not be exposed.

It is a further object of the invention to provide an electric connector and insulator for supporting the same, such electric connector being of simple form and being adapted to be secured to the insulator without the use of tools and having a terminal to which a feed wire may be connected and also having a contacting member for engaging an electric device to which the electric current is to be fed.

It is another object of my invention to provide an insulator of tubular character adapted to receive the rearwardly bent end of a glow tube, the insulator having electric connecting means supported thereby through which electric connection with the electrode at the end of the tube is made in such a manner that no stresses are applied to the tube which might tend to break the same, and in such a manner that change in relative size of the cooperating members due to temperature changes will not result in breaking the glow tube.

It is a further object of the invention to pro-

vide the electric connecting means supported by the insulator with a terminal to which an electric lead may be directly attached, thus obviating the necessity of providing separate supporting and attaching means for the lead.

It is another object of the invention to provide a tubular insulator adapted to extend through a supporting wall and to receive the end of a glow tube, and a connecting means mounted on the insulator in a novel manner, so that the tube extends entirely through the insulator and contacts the connecting means at a point beyond the end of the insulator whereby snow, rain or dirt collecting within the tubular insulator will not tend to cause short-circuiting between the connecting means and the wall supporting the insulator.

Further objects and advantages of the invention will be made evident throughout the following part of the specification.

Referring to the drawing, which is for illustrative purposes only,

Fig. 1 is a perspective view showing a preferred form of my invention.

Fig. 2 is a longitudinal sectional view through the device shown in Fig. 1.

Fig. 3 is an end view, to an enlarged scale, of the electric connector embodying the features of my invention, this view being partly sectioned.

In the form of the invention shown in the drawing, the sign supporting structure may include as a part of the front wall thereof a metal wall 30. This metal wall 30 will, in the ordinary practice of the invention, consist of a thin metal sheet, but, as will be evident from the following part of the specification, the wall may be of any desired thickness. The wall 30 has a circular opening 32. An insulator member 34 is provided which is preferably of tubular form, as shown in Figs. 1 and 2, and may be molded or formed of any known insulating material selected in accordance with the dielectric characteristics required of the insulator, which of course will be determined in accordance with the voltages to be insulated against. The insulator member 34 has a front end 36 of such external shape that it will fit into the opening 32 of the wall 30. In the general use of the invention, the end 36 preferably is of sufficient length to extend entirely through the wall 30 and project outwardly a substantial distance from the front face of the wall 30, as shown in Fig. 2, for a purpose which will hereinafter be brought forth. However, it is not essential in all instances that the end 36 project entirely through a wall. Adjacent the end 36, the insulator member 34 is provided with

a flange or rib 38 adapted to abut the rear face of the wall 30. The flange 38 may be secured to the wall 30, by suitable means such as that illustrated in the drawing, and generally indicated by the numeral 40.

Mounted on the inner or rearward end of the insulator member 34 is an electric connecting means, generally designated by the numeral 44. In the making of electric contacts with the electrodes on the ends of neon tubes, it is customary to mount a separate terminal post on the rear face of the supporting wall. The electric lead wire of the energizing circuit is then connected for support to one of these posts, and another wire is carried from the post to the electrode fitting at the end of the neon tube. The electric connecting means 44 of my invention provides a simple, practical means of making connection between the lead wire of the energizing circuit and the electrode fitting of the tube without the use of separate terminal posts such as just referred to. The electric connecting means 44, as shown in the drawing, comprises a member 45 adapted to be clamped on the cylindrical portion 25 or boss 46 constituting the rearward end of the insulator member 34. The member 45 carries a terminal 47, preferably of the spring clip type, to which an electric wire 48 may be directly attached, as shown in Fig. 1. The member 45 also 30 carries a contacting or connecting member 49 adapted to engage the metal electrode fitting 51 at the extremity of the end 41 of a neon tube 42 which is extended rearwardly into the opening or bore 43 of the tubular insulator 34, thereby 35 passing through the opening 32 of the wall but being insulated therefrom. The member 45 preferably consists of a strip of metal which is bendable, or bent, to circular form so that the ends 52 and 53 thereof are brought into close relation. 40 The end 52 is provided with a tongue 54 adapted to pass through a slot 55 in the end 53 when the member 45 is closed around the boss or end 46 of the insulator member 34, whereupon the end of the tongue 54 may be bent rearwardly so 45 as to hold the member 45 in contracted relation. The member 45 is preferably provided with openings 56 adapted to receive lugs 57 which are formed near the end of the insulator member 34. The lugs 57 and the openings 56 provide a means 50 of interengagement between the boss 46 and the electric connector which will prevent removal of the electric connector from its position on the insulator 34 unless the tongue 54 is disengaged from the opening 55 and the member 45 sprung 55 open to such diameter that the lugs 57 may be moved out of the openings 56.

It is a feature of my invention that the contacting or connecting member 49 is adapted to engage the electrode fitting of the neon tube 42, 60 in such a manner that the high voltage energizing current will be transmitted to the fitting 51 without the application of strains of a character tending to break the neon tube, and in such a yieldable manner that changes in position of the 65 cooperating parts of the entire sign structure will not produce stresses to break the neon tube. As shown in the drawing, the contact member 49 extends inwardly from the member 45 across the rear end of the insulator. This member 49 70 is preferably made in the form of a spiral of bronze wire 70 having its outer end 71 connected at two places to the member 45. Two small bridges 72 and 73 are punched inwardly from the wall of the member 45 and the outer end 75 71 of the wire 70 is passed through these bridges

or loops 72 and 73 and there secured either by use of solder or by deforming the bridges 72 and 73 by pressure so that they will bear tightly against the wire 70. The spiral contacting member 49 is of resilient character, and the central portion 74 thereof is adapted to bear resiliently against the electrode fitting 51 when the end 41 of the neon tube 42 is moved rearwardly to extend through the opening 43 of the insulator member 34. As best shown in Fig. 2, the contacting member 49 is positioned in relatively spaced relationship with the end of the insulator 10 34. This leaves the entire length of the opening 43 of the insulator member 34 unobstructed, which greatly reduces the tendency for snow, 15 rain, dirt or the like to collect within the opening 43 of the insulator in sufficient quantities to cause a short-circuit between the contacting member 49 and the wall upon which the insulator is mounted. As before stated, the end 36 of the insulator 34 is preferably of sufficient length to project outwardly from the front face of the wall 30 for the reason that this assists in preventing short-circuiting between the contacting member 49 and the wall 30 through an accumulation 20 of snow or dirt in the interior of the insulator 34. The open construction of my device as a result of the relative spacing of the contacting member 49 from the end of the insulator 34, however, is such that there is little tendency 25 for snow or dirt to collect within the insulator so that even though the insulator is mounted in a wall of such thickness that the end 36 does not project entirely therethrough, short-circuiting between the contacting member 49 and the 30 wall is unlikely.

If the end 41 of the neon tube 42 is short, the central portion 74 of the contacting member 49 may be bent or deformed in the direction of the axis of the insulator member 34 so as to extend 40 inwardly of the member 34 to engage the fitting 51 without obstructing the opening 43 surrounding the fitting 51 and the end 41 of the neon tube. If the end 41 should be longer than is shown in Figs. 1 and 2, the electrode fitting 51 will merely 45 deflect the central portion of the member 49 rearwardly or leftwardly so that contact is made without producing stresses which might break the neon tube.

Although I have herein shown and described 50 my invention in simple practical form, it should be clear that certain parts or elements thereof are representative of other parts, elements, or mechanisms which may be used in substantially the same manner to accomplish substantially the 55 same results; therefore, it is to be understood that the invention is not to be limited to the details disclosed herein, but is to be accorded the full scope of the appended claims.

I claim as my invention:

1. A device of the character described for providing electrical connection with an electric means at an aperture in a wall, said device including: a hollow insulator dimensioned to receive a portion of said electric means, said insulator being open at both ends and being adapted for mounting in said wall aperture; and an electric connecting means comprising a ring embracing said insulator, a terminal on said ring outside of said insulator for connecting an 70 electric feed conductor, and a contacting member across the opening through said insulator consisting of a spiral of metal having its outer end connected to said ring.

2. A device of the character described for pro-

viding electrical connection with an electric means at an aperture in a wall, said device including: a hollow insulator dimensioned to receive a portion of said electric means, said insulator being open at both ends and being adapted for mounting in said wall with the forward end of the insulator extending through said aperture; and an electric connecting means comprising a ring surrounding said tubular insulator, a terminal on said ring for connection with an electric feed conductor, and a yielding contact member connected with said ring and extending across the rear open end of said insulator in spaced relationship therewith.

15. 3. A device of the character described for providing electrical connection with an electric means at an aperture in a wall, said device including: a hollow insulator dimensioned to receive a portion of said electric means, said insulator being open at both ends and being adapted for mounting in said wall aperture; and an electric connecting means mounted on said insulator, said connecting means comprising a strip fitting around said insulator, means releasably connecting the ends of said strip together thereby clamping said strip on said insulator, a terminal on said strip to which an electric feed connector may be connected, and a contacting member carried by said strip and extending inwardly across the opening of said insulator.

20. 4. A device of the character described for providing electrical connection with an electric means at an aperture in a wall, said device including: a hollow insulator dimensioned to receive a portion of said electric means, said insulator being open at both ends and being adapted for mounting in said wall aperture; a ring member releasably embracing said insulator at one end thereof a terminal on said ring member outside of said insulator for connection with an electric feed conductor; and a contact member mounted on said ring member and extending inwardly across the opening of the insulator.

25. 5. A device of the character described for providing electrical connection with an electric means at an aperture in a wall, said device including: a hollow insulator dimensioned to receive a portion of said electric means, said insulator being open at both ends and being adapted for mounting in said wall aperture; and an electric connecting means mounted on said insulator, said connecting means comprising a strip in ring form contracted around said insulator, said insulator and said strip being so formed as to provide interengagement against relative axial

movement therebetween, a terminal on said strip to which an electric feed conductor may be connected, and a contact member carried by said strip and disposed across the opening of said insulator.

6. A device of the character described for providing electrical connection with an electric means at an aperture in a wall, said device including: a hollow insulator dimensioned to receive a portion of said electric means, said insulator being open at both ends and being adapted for mounting in said wall aperture; a ring member encircling said insulator, said insulator and ring member being so formed as to provide releasable interengagement between them for preventing axial movement of the ring member relative to the insulator; a terminal on said ring member to which an electric feed conductor may be connected to energize the ring member; and a spiral contact member having its outer end connected to said ring member, said spiral contact member being disposed across the opening through said insulator.

7. A device of the character described for providing electrical connection with an electric means at an aperture in a wall, said device including: a hollow insulator dimensioned to receive a portion of said electric means, said insulator having a peripheral projection; a ring member releasably embracing said insulator, said ring being in engagement with said peripheral projection from opposite sides thereof to prevent relative axial movement between the ring member and insulator; a terminal carried by said ring member for connecting an electric feed conductor therewith; and a contact member carried by said ring member, said contact member extending inwardly across the opening through the insulator.

8. A device of the character described for providing electrical connection with an electric means at an aperture in a wall, said device including: a hollow insulator dimensioned to receive a portion of said electric means, said insulator having a peripheral projection; a ring member releasably embracing said insulator in positive engagement with said peripheral projection to prevent axial movement of the ring relative to the insulator; a terminal carried by said ring member for connecting an electric feed conductor therewith; and a spiral contact member disposed across the opening through said insulator, the outer end of said spiral contact member being connected to said ring member.

MILTON M. KAUFFMAN.
